INVENTOR

WM. W. REYNOLDS.

UNITED STATES PATENT OFFICE.

WILLIAM W. REYNOLDS, OF RUTLAND, VERMONT.

DESIGN FOR A SUPPORT FOR THE WEIGH-BEAMS OF SCALES.

SPECIFICATION forming part of Design No. 16,606, dated April 6, 1886.

Application filed December 17, 1885. Serial No. 186,014. Term of patent 14 years.

To all whom it may concern:

Be it known that I, WILLIAM W. REYNOLDS, a citizen of the United States, residing at Rutland, county of Rutland, and State of Vermont, have invented and produced a certain 5 new and original Design for Support for the Weigh-Beam of a Scale, fully described and represented in the following specification and the accompanying illustration, forming a part 10 of the same.

My design relates particularly to the means employed for supporting the weigh-beam and other parts which are above the platform of a scale. The design is especially adapted for 15 those scales which are known as "platform counter-scales," but it may be applied to other classes of scales.

The principal features of my design are two 20 columns or pilasters, which rise from the base of the scale at one side of the platform, a cap-plate, which rests upon the tops of these columns or pilasters and extends beyond the ends of the weigh-beam and supports two stands, one having the fulcrum-pivot for the 25 weigh beam and the other the latch for locking the beam, and an ornamental arch, which springs from the ends of the cap-plate and spans the space occupied by the weigh beam.

As my design can be best understood from 30 a detailed description of the same, such description will now be given, reference being had to the accompanying illustration, which shows the design applied to a platform counter-scale.

Referring to said illustration, it is to be understood that C are two columns or pilasters, which rise from the base of the scale at one side of the platform. These columns or pilasters may be of any desired form in cross-section, and may be provided with ornamental bases and capitals, a b. Upon the tops of the 35 columns or pilasters C rests a cap-plate, D,

which extends beyond the ends of the weigh-beam and supports two stands, c d, the former of which supports the fulcrum-pivot for the 45 weigh-beam, while the latter supports the usual latch for locking the beam. From the ends of the plate D, which extend beyond the ends of the weigh-beam, springs an arch, F, which spans the space above the same. The 50 columns or pilasters C, cap-plate D, stands c d, and arch F may be provided with any suitable ornamentation. The ends of the cap-plate D, which support the arch F, may be curved upward, as shown, and the cap-plate 55 may also be in one piece, extending entirely across the space between the columns or pilasters, as also shown; but these features are not essential.

What I claim is—

1. The design for a support for the weigh-beam of a scale, consisting of two columns or pilasters, a cap-plate, which rests upon the tops of said columns or pilasters and projects beyond them, and an arch, which springs from 65 the ends of the cap-plate and spans the space above the same, substantially as shown and described.

2. The design for a support for the weigh-beam of a scale, consisting of the two columns 70 or pilasters C, the cap-plate D, which rests upon the tops of said columns or pilasters with its ends projecting beyond them, the stands c d, resting upon the plate D, and the arch F, springing from the ends of the plate D and 75 spanning the space occupied by the stands c d, substantially as shown and described.

In testimony whereof I have hereunto set my hand in the presence of two subscribing witnesses.

WM. W. REYNOLDS.
